Primary Examiner — Catherine S Posthauer*Assistant Examiner* — Amina Rahman*(74) Attorney, Agent, or Firm* — Bernard S. Hoffman**CLAIM**

I claim the ornamental design for a magnetic button, as shown and described.

DESCRIPTION

FIG. 1 is a perspective view of a magnetic button according to this design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top plan view thereof.

The dot-dash lines represent the boundaries of the claim and form no part thereof.
